UNITED STATES PATENT OFFICE.

WILLIAM BROWN, OF GLASGOW, SCOTLAND.

IMPROVEMENT IN PREPARING PARAFFINE-OIL.

Specification forming part of Letters Patent No. 10,055, dated September 27, 1853.

To all whom it may concern:

Be it known that I, WILLIAM BROWN, of the city of Glasgow, in the county of Lanark, Scotland, have invented or discovered improvements in treating coal and other bituminous substances, and for treating the volatile products resulting therefrom; and I do hereby declare that the nature of my said invention and the manner in which the same is to be performed are fully described and ascertained in and by the following statement thereof, reference being had to the drawings hereunto annexed, and to the figures and letters marked thereon—that is to say:

The first operation consists in distilling the coal or other bituminous matter in conjunction with steam at a dull-red heat, for which purpose the coal is introduced into a retort fitted with a steam-pipe so situated as to become red-hot by passing through the furnace. This steam-pipe terminates in the closed end of the retort, so that when the retort is charged with coal or other bituminous substances and the furnace is in action the steam-pipe becomes red-hot, and steam being passed along it, this also becomes red-hot, and in this state enters the end of the retort and rapidly expels the volatile matters arising from the coal or other bituminous substances, by which their decomposition into gas is wholly or in great measure prevented and the amount of oily or condensable products greatly increased. Figure 1 in the annexed sketch shows the disposition of the retort and steam-pipe. Having by this means obtained a quantity of volatile products from coal or other bituminous substances, these are again subjected to distillation in a still or other convenient vessel, with or without the employment of a steam-pipe, though I prefer to use steam when a large amount of paraffine is required; but where the production of oil is the chief object steam may be dispensed with. When steam is used, this is to be brought into the still in a superheated state by passing it through a red-hot steam-pipe disposed in the furnace or flue of the furnace which heats the still. The steam enters through the upper part of the side of the still, as shown in Fig. 2, and promotes, as before, the distillation of the volatile matters, while it retards their destruction or conversion into gaseous or other worthless compounds. By this means the paraffine

and heavy hydrocarbonaceous oils are preserved.

During the progress of the second distillation it will be observed that the products vary at different periods of the distillation, and these are, therefore, to be kept separate or received in different vessels. At first a thin oil or euphone comes over to the extent of about one-eighth of the total fluid employed. After this a thicker and heavier oil containing paraffine makes its appearance to the extent of from forty to fifty per cent. of the fluid, employed; and, lastly, a thick butyraceous matter is evolved, consisting chiefly of paraffine, but mixed with heavy oil, and this continues to the end of the operation, and constitutes about one-fourth of the bulk of the fluid originally used. These three products are treated as follows: The euphone is mixed with from five to ten per cent. of its weight of oil of vitriol or sulphuric acid, to which an equal bulk of water is added before mixing. To these bichromate of potash is next thrown in equal in weight to one-half of the sulphuric acid employed. The whole is then heated in any convenient vessel of wood or lead or earthenware, and during the heating the materials are diligently stirred together. As soon as the temperature has reached 212° Fahrenheit the fire may be withdrawn and the whole permitted to cool and settle. The euphone is next decanted from the acid fluid and treated with a warm solution of caustic soda, the whole being well mixed and afterward left at rest for some time to settle. Lastly, the euphone is decanted from the alkaline fluid and distilled either alone or with water or steam, as is practiced with respect to volatile oils generally. The heavy oil containing paraffine is next treated either with strong sulphuric acid and peroxide of manganese in the proportion of ten per cent. of acid and five per cent. of peroxide of manganese; or, what I prefer, it is subjected, like the euphone, to the action of sulphuric acid and bichromate of potash in the same manner and proportion as indicated for the euphone, after which it is treated with soda lye and allowed to settle, exactly as explained with regard to the euphone. The heavy oil is then decanted and distilled in the usual way; the first portions being added to the euphone as consisting chiefly of that substance. The second and by

far the larger portion of the whole is received apart under the name "lubricating-oil," while the last portions, being thick and of the consistence of butter, are mixed with the impure paraffine which results from the third stage of the second distillation of the crude products, and which are treated as follows: Having allowed the impure paraffine to remain for twenty-four hours or longer in a cool place to crystallize, the oily mixture is placed in a bag or filter similar to those in use for the separation of spermaceti from sperm-oil. When the oily fluid has drawn away, the paraffine must be removed to a press and subjected to severe pressure, as is practiced with respect to stearic acid by the makers of that substance. It must then be melted, and when cold again pressed, the oil being in both cases added to the drainings, which are to be treated as explained under the head "heavy or lubricating oil." The paraffine must now be melted and the heat raised to about 400° Fahrenheit, when strong sulphuric acid is to be carefully stirred into it in the proportion of one-twentieth to one-tenth of the weight of the paraffine operated upon. After boiling for a few minutes the fire must be withdrawn and the charred oil of the paraffine allowed to settle in the form of a black powder from the paraffine. This being separated, the paraffine

must be boiled in water or in a weak solution of soda, after which it may be cooled, and is fit for the market

I am aware that paraffine-oil has been obtained by heating bituminous coal in a closed retort up to a dull or low red heat, and passing the volatile products of the distillation through a refrigerator kept at a temperature of about 55° Fahrenheit.

I am also aware that paraffine-oil thus obtained has been purified by being put into a cistern heated by a steam-pipe or other means to a low temperature of about 150° Fahrenheit, and subsequently more or less heated with oil of vitriol and caustic soda and subjected to distillation. I herein make no claim to such a mode of obtaining and purifying paraffine; but

I claim—

1. The use of superheated steam as is indicated, for the purpose indicated.
2. The mode of separating and purifying the eupine, lubricating-oil, and paraffine obtained by previous process.

WILLIAM BROWN.
